UNITED STATES PATENT OFFICE.

BRUNO B. CHOINSKI, OF MILWAUKEE, WISCONSIN, ASSIGNOR OF FORTY-NINE ONE-HUNDREDTHS TO ALEXANDER B. CHOINSKI, OF MILWAUKEE, WISCONSIN.

HEATING ATTACHMENT FOR STOVE AND FURNACE PIPES.

Application filed April 5, 1922. Serial No. 549,896.

To all whom it may concern:

Be it known that I, BRUNO B. CHOINSKI, a citizen of the United States, residing at Milwaukee, county of Milwaukee, and State 5 of Wisconsin, have invented new and useful Improvements in Heating Attachments for Stove and Furnace Pipes, of which the following is a specification.

This invention relates to heating attachments 10 for stove and furnace pipes.

It is the object of this invention to provide means for extracting to an extent hitherto impossible all heat from exhaust gases which are ordinarily delivered in a highly heated 15 condition to the chimney or smoke-stack.

More specifically it is the object of this invention to provide passages for air to be heated interiorly and exteriorly of the flue or passage for the heated gases.

20 It is a further object of this invention to provide in combination with the air heating means above referred to, means for elongating within a minimum space the flue or passage for the heated gases, whereby said gases may be afforded a maximum opportunity, 25 within the space available, for transmitting their heat to the air.

The elongation of the gas passages is brought about by providing a helical flange 30 between coaxial, cylindrical walls, thereby causing the gases to follow a helical path. A further economy of heat is effected by providing in combination with the helical flange above referred to, a pipe or tube adapted to 35 convey a liquid which may also be used to effect economies by saving heat which would otherwise be lost. As will hereinafter be pointed out, the position of the tube with respect to the remaining elements of this device is such that the tube is at all times subjected to the heat of the main body of gas 40 passing through the device.

In the drawings,—

45 Figure 1 represents a longitudinal, vertical section through a device embodying this invention.

Figure 2 is a transverse section through the device illustrated in Figure 1.

50 Like parts are identified by the same reference characters throughout the several views.

The pipe through which the heated gases are led into the device is shown at 5, and the pipe leading from the device to the chimney is designated by the numeral 6. Each

of the pipes or flues 5 and 6 is provided with 55 a damper, 7 and 8, respectively.

A drum 9 is provided with a plurality of openings 10 in its bottom adapted to permit the ingress of air. A register pipe 11 in communication with the interior of the drum 60 is provided for the purpose of conveying heated air therefrom through the register 12 to the interior of a room indicated diagrammatically at 13, which is to be heated.

Within the drum 9 is a pair of cylinders 65 14 and 15, which are preferably coaxial. The interior of cylinder 14 is in communication at its ends with the pipes 5 and 6, which convey the heated gases. The ends of cylinder 15 are closed, and said cylinder 70 is provided with an inlet pipe 16 which opens into the outer air, and with an outlet pipe 17 which discharges into the upper portion of the drum 9. The inlet and outlet serve to permit air to be admitted freely to 75 the interior of cylinder 15, and having been heated therein, to pass upwardly with the air heated in drum 9 into the room 13.

Between the cylinders 14 and 15 there is 80 preferably interposed a helical flange 18 which is coiled about cylinder 15 from one end to the other thereof. The flange 18 obviously serves to form a helical passage between cylinders 14 and 15 adapted to cause the heated gases traveling between said cylinders to follow a helical path. It is not desired, however, that the gases acquire too rapid a rotation through being forced to follow the path described by the flange 85 18, and for the purpose of breaking up to some extent the whirling motion which would otherwise be induced in the gases, openings 90 19 are provided as shown at intervals in flange 18. The relatively small amounts of gases which will pass through the opening 95 19 will serve to check the whirling motion in the remainder of the gases, which would otherwise cause all of said gases to be thrown by centrifugal force against the cylinder 14. To some extent, however, the bulk of the 100 gas will be thrown outwardly against the inner wall of cylinder 14, thereby forming a relatively dense layer of heated gas adjacent said wall.

To facilitate the transfer of heat from the gases arriving through the pipe 5, I have provided a tube or pipe 20 which is wound at 21 into a coil against which the incoming

gases will impinge. From the coil 21, the pipe 20 is led about the exterior margin of the helical flange 18, preferably conforming substantially thereto. The pipe 20 is 5 adapted to convey a liquid, and it is particularly to be noted that the disposition of this pipe within the heat transferring device is such that the pipe will at all times lie in contact with the most dense portions 10 of the heated gases, from which it is desired to exhaust the heat. A coil 22, similar to coil 21 may, if desired, be provided adjacent the discharge end of the device, and thence the tube or pipe 20 is led outwardly and 15 may be connected with suitable piping to a radiator 23, whence the return pipe leads to the inlet end of tube 20.

It will be noted that the device of my invention occupies a relatively small space, 20 due to the provision of helical flanges, which cause the heated gases to remain for an extended period in confinement between the drums 14 and 15. Upon each side of the confining walls fresh air is supplied unrestrictedly, and such air having been heated by the whirling gases is delivered upwardly 25 to a room, in which the heat imparted thereto can be utilized. In stating that the air is supplied unrestrictedly, I refer to the 30 normal operation of my device, but I desire it to be understood that dampers may be provided as desired. Such a damper is shown at 25, and is adapted to shut off the admission of air to the interior cylinder 15. 35 A similar damper may be provided in tube 11 to prevent the too rapid passage of heated air into room 13, if necessary.

It will be obvious that the transfer of heat can be controlled to a considerable extent by means of dampers 7 and 8. If both 40 of said dampers are open, the gas will rush through the device with considerable velocity. If damper 7 is closed it will tend to check the operation of the furnace or 45 other combustion chamber with which this device is associated. On the other hand, if damper 7 is open and damper 8 is closed, the furnace will likewise be checked, but such gases as are produced therein will be 50 permitted to enter the heat transferring device of my invention, and the heat will be utilized.

I claim:

1. A device of the class described including an internal cylinder, an external cylinder, a helical flange interposed between said cylinders, means for admitting heated gases to the space between said cylinders and conveying said gases from said space, a drum 55 enclosing the outer cylinder, means for admitting air thereto, and means for conveying

65 away air heated therein said helical flange having a series of spaced apertures, whereby to prevent excessive whirling of gases between said cylinders.

2. A device of the character described comprising a horizontal flue portion, a cylinder in said flue portion closed to gases passing therethrough, a drum surrounding said flue portion and providing an air chamber, a hot air pipe leading from the upper portion of said drum, a cold air pipe passing through the bottoms of said drum and flue portion and into the bottom of said cylinder, and a second hot air pipe passing from the upper portion of said cylinder through the top of said flue and into said drum, said drum having a perforated bottom.

3. A device of the character described comprising a horizontal flue portion, a cylinder in said flue portion closed to gases passing therethrough, a drum surrounding said flue portion having a hot air pipe leading from the upper portion of said drum, a second hot air pipe leading from the upper portion of said cylinder and into said drum, a cold air pipe passing through the bottom of said drum and flue portion and into said cylinder, and a damper in said cold air pipe, whereby the rate of delivery of heated air from the 90 drum may be regulated.

4. A device of the class described, including a helical conduit connected at its ends into a chimney flue, a helical pipe within 95 said conduit and conforming substantially to the outer margin thereof, a radiator and connections between the radiator and said pipe.

5. The combination with a flue, and a section thereof having an increased cross-sectional area, of a cylinder closed at its ends mounted within said section, a helical flange wound about the cylinder between it and the wall of said section, means for admitting air to the cylinder, a drum enclosing the enlarged section of the flue and in communication with the interior of the cylinder, means for admitting air to the drum, said means comprising a perforated bottom and a pipe adapted to deliver heated air therefrom.

6. The combination with a flue and an enlarged section therein, of a cylinder within 110 said section closed against the passage of flue gases, a helical flange wound about the cylinder between it and the wall of said section, a drum surrounding said section, means for permitting air to circulate through said drum, a pipe conforming to the outer margin of said helical flange, and a radiator connected in a closed circuit with 115 said pipe.

BRUNO B. CHOINSKI
